Patented Jan. 7, 1958

181,872

LIFT TRUCK

Kenneth H. Mindrum, Battle Creek, Mich., assignor to Clark Equipment Company, a corporation of Michigan

Application December 24, 1956, Serial No. 44,306

Term of patent 14 years

(Cl. D14—3)

FIG. 1

Des. 181,872

PAGE 2

FIG. 2

Des. 181,872

PAGE 3

FIG. 3

FIG. 4

I claim:

The ornamental design for a lift truck, as shown.
